UNITED STATES PATENT OFFICE

2,531,290

STRIP CASTING MACHINE

Anton H. Narrow, Memphis, Tenn.

Application April 12, 1948, Serial No. 20,505

2 Claims. (Cl. 22—57.2)

1

This invention appertains to novel and useful improvements in devices for casting strips for use in association with printing.

An object of this invention is to form and cut strips of material in an improved manner.

Another object of this invention is to form and cut strips of material by means of a device which is extremely inexpensive both in operation and initial cost.

Another object of this invention is to feed a supply of plastic material, preferably metallic, in the molten or semi-molten state and, simultaneously, separate a charge of this molten material from the supply, admix a lubricant with the charge while urging a previous charge through a mold, cool the molten material while a charge thereof is being urged through a mold, thereby forming a continuous strip of solidified material.

Another object of this invention is to intermittently pull the strip from the mold and hold the pulled strip while cutting it to size.

A still further object of this invention is to cut the strip in pre-selected lengths, the cutting being initiated in response to the length of travel of the continuous strip.

A still further object of this invention is to compensate for various widths of continuous strip material while holding it during the cutting operation.

A still further object of this invention is to hold the strip in such a manner while it is being cut and after it has been cut in order to prevent obstructions in the advance of the continuous strip.

Another object of this invention is to intermittently advance the continuous strips at selected speeds and periodically hold the strip at the proper interval for cutting purposes.

Yet another object of this invention is to cut the continuous strip to pre-selective lengths, the cutting means being responsive to the actual length of the molded strip.

Another object of this invention is to provide an improved mechanism with no pivot pins in or adjacent the crucible or heating pot, thereby preventing inefficiency in operation resulting from swollen pivots (due to the heat).

Another purpose of this invention is to prime the apparatus by manual means, thereby preventing breakage of the device due to premature mechanical operation (while the plastic material has not yet reached the molten or semi-molten stage).

Another object of this invention is to lubricate the molten or semi-molten plastic material while

2

it is being separated from the supply in charges, which separation urges a previous charge through a mold in order to form a continuous, unbroken, homogeneous strip.

Another object of this invention is to separate the charges of plastic material from the supply by means of the actuation of a piston, which piston is resiliently loaded on the upstroke, the resiliency being the motive force during the downstroke, which downstroke is the actual power stroke.

Another object of this invention is to provide a smoothly operative device of the nature to be described which is self-contained, requiring merely an electrical outlet for actuation purposes.

Another purpose of this invention is to provide means for regulating the amount of charge which is separated from the supply of molten material in order to compensate for leakage around the piston head, thereby making it possible to separate substantially identical (in quantity) charges of material.

Ancillary objects and features of novelty will become apparent to those skilled in the art, in following the description of the preferred form of the invention, illustrated in the accompanying drawings, wherein:

Figure 1 is a perspective view of the preferred form of the invention;

Figure 2 is a perspective view of a stripped down plate whereon several operative portions of the device reside;

Figure 3 is an elevational side view of the invention shown in Figure 1;

Figure 4 is an end view of a mechanism for adjusting the stroke of the puller;

Figure 5 is a sectional view taken substantially on the line 5—5 of Figure 4 and in the direction of the arrows;

Figure 6 is an elevational side view of the preferred form of the invention, portions being broken away in section to illustrate details of construction;

Figure 7 is a plan view of a pulling mechanism, which is substantially identical in structure to the locking mechanism;

Figure 8 is a sectional view taken substantially on the line 8—8 of Figure 7 and in the direction of the arrows;

Figure 9 is an enlarged sectional view of the crucible used in the invention, illustrating particularly the lubricating means and means for separating charges of molten material from a supply;

Figure 10 is a plan view of the cutter mech-

anism forming a portion of the present invention;

Figure 11 is an elevational view of the detail of construction shown in Figure 10;

Figure 12 is a front view of the cutter mechanism;

Figure 13 is a perspective view of a plug used for regulating the stroke of the cutter mechanism in order to compensate for various widths of strips being cut;

Figure 14 is a plan view of the invention shown in Figure 1, a portion of the piston mechanism being broken away in order to illustrate certain details;

Figure 15 is an enlarged fragmentary plan view of the device shown in Figure 14, showing the cutter mechanism in a second operative position; and

Figure 16 is a sectional detail of construction taken substantially on the line 16—16 of Figure 9 and in the direction of the arrows.

Frame or support

A suitable support or frame is supplied as the recipient of various elements of the invention and may be made of any suitable material including either cast or angle iron braces and the like. Four legs 10, 12, 14 and 16, respectively, may be supplied with a platform 18 associated therewith for accommodating a suitable motor 20. It will be noted at this point that the said motor 20 may be of any conventional nature having the usual conductor or lead 22 extending therefrom. This lead may be attached to the platform 18 through the medium of a conventional clamp 24 and may have a switch 26 associated therewith for making and breaking an electrical circuit, thereby rendering the motor 20 operative, when it is found desirable. Also, the said motor 20 may be attached to the platform 18 by any suitable means such as bolts, rivets, or the like. It is also within the purview of the present invention to adjustably mount the motor 20, since it has a pulley 28 associated therewith with a V-groove belt 30 entrained about the pulley. In cases wherein the tension of the belt 30 is to be adjusted, this may be effected by movement of the motor.

The support or frame includes a substantially flat top 32 having an aperture 34 therein. Viewing Figures 1 and 14, it will be seen that the top 32 is substantially planar and unobstructed for the major portion thereof and said recess 34 is formed as a well for accommodation of a crucible or melting pot 36 (see Fig. 9).

A stripped down plate 38 (Figure 2) is attached to one side of the top 32 by means of suitable bolts or the like passing through the apertures 40 provided at the proper positions on this plate. Various cutouts and recesses are supplied in this plate 38 in order to accommodate various mechanisms forming a portion of the present invention.

Suitable side supports 42, 44, and 46 are interconnected with the legs and also serve the purpose of a recipient for various mechanisms in the invention.

Heating system

The crucible 36 is adapted to receive plastic (preferably metallic) stock which is melted to a certain stage of fluidity which is considered molten. The degree of fluidity requisite in the efficient operation of the invention may be ascertained by the operator of the device. The ma-

terial must not be heated to a state wherein the viscosity is substantially zero, and yet the material must be heated enough in order to permit free flow of the same through various conduits. In order to effect this heating, many means may be employed. However, the preferable means is by utility of a gas manifold with various conduits associated therewith.

An inlet conduit 48 which is connected to a suitable gas source is attached to the frame or support leg 16 by any suitable means, such as a pipe clamp 50. This inlet conduit 48 has a plurality of branch conduits associated therewith, one of which is seen at 52. This branch conduit has a valve generally indicated at 54 therein which is of the manual operational type. A conventional burner 58 is connected therewith and extends beneath the melting pot or crucible 36. Of course, suitable regulatable air inlet valve means for mixture control may be supplied, as is seen at 60.

A pair of conventional valves 62 and 64, respectively, are communicated with the inlet pipe 48 and have tubes 66 and 68, respectively, communicated therewith. These tubes terminate adjacent the mold cell and valve mechanism for maintaining the cell and mechanism in a relatively hot condition in order to allow free flow of molten material therethrough.

Means for separating charges of material from the supply

Viewing Figure 1, it will be seen that a pair of rails 70 and 72, respectively, are supplied in association with the plate 38. These rails 72 and 70, respectively, may be formed of any suitable material such as angle iron or the like and rigidly associated with the said plate 38 by means of conventional bolts, rivets, or even welded if it is found desirable. As is seen in Figure 3, a through passage is supplied between the said rails 70 and 72 in order to accommodate a reciprocating rod 74. This rod is bifurcated at one end thereof, forming a pair of divergent arms 76 and 78. At the point of inception of the divergency, a notch 80 is formed for accommodation of a rocker arm 82. It will be noted that the external dimensions of the rocker arm 82 are substantially identical to the internal dimensions of the notch 80 wherein a firm seating may take place.

A boss 84 is formed integral with an extension 86 of the said rod 74. This extension 86 extends between the rails 70 and 72 and has a piston rod 88 associated therewith. This piston rod 88 extends through the boss and is secured thereto by means of a conventional pin 90. Of course, the pin extends through the boss as well as through the said piston rod 88 to form the necessary firm clamping effect.

A shoe 92 including a main block reciprocatively mounted between the rails 70 and 72 is supplied. This shoe has an apertured extension 94 integral therewith for accommodation of the piston rod 88 therethrough. The said shoe 92 may include a plate 96 which is attached to the main center block thereof by means of adjustable threaded elements or bolts 98. These bolts, of course, penetrate the said plate 96 and terminate in the center block for firmly clamping this mechanism in the selected adjusted position relative to the longitudinal axis of the rails 70 and 72.

A conventional spring 100 or any other suitable equivalent resilient biasing means encircles the said piston rod 88 bearing on the said extension 94 and the said boss 84. When the said

rocker arm 82 is manipulated, it is now apparent that the boss 84 reciprocates for storing potential energy in the spring 100. On the upstroke of the boss 84, the potential energy is stored in the said spring 100 and on the downstroke it is 5 the actual energy stored within the spring that supplies the motive force of the piston rod 88. By adjustment of the shoe 92, the amount of force stored in the spring may be regulated in order to arrive at the most effective speed of 10 downstroke of the piston rod and also in order to arrive at the most smoothly operative condition of the apparatus.

Referring now to Figure 9, it will be seen that the said piston rod 88 has a piston head 102 secured thereto with grooves 104 formed therein. The said piston rod and piston reciprocate in cycles of operation, urging the piston head 102 in a cylinder 106. This cylinder 106 is supplied in a relatively heavy block 108 which is secured with- 15 in the crucible 36.

A bracket 110 (see Fig. 14) is secured to an edge of the frame or support extending over the aperture 34. A stay bolt 112 extends through the bracket 110 and rests upon the edge of the block 20 25 108 for support purposes.

The said block 108 is supplied with a pair of apertures or bores 114 and 116, respectively, which are diametrically placed adjacent the lower portion thereof and which communicate with the 30 said cylinder 106. Noting first the said bore 116, it will be seen that an elbow 118 is secured thereto and has a conduit 120 threadedly associated therewith. Of course, if it is found desirable, the elbow, conduit, and block 108 may be formed as a single unit, this being within the prerogative of the manufacturer.

One end of the said conduit 120 has its bore internally threaded in order to accommodate the threaded portion 122 of a valve stem 124. This valve stem has a reduced terminal portion cooperative with a valve seat formed at 126 in the 40 said conduit 120. Various inlet channels 128 and 130, respectively, are formed laterally of the bore of the said conduit 120 at a point adjacent the valve seat 126 for inlet purposes. Of course, the opposite terminal of the said valve stem 124 may be flattened either hexagonally, square, octagonally, or in any other suitable shape for manipulation purposes. By adjustment of this valve 45 stem 124 in the bore of the said conduit 120, the opening at the valve seat 126 is selectively regulated in order to permit a selected amount of molten material to be pulled into the cylinder 106 by the negative pressure or suction created therein upon actuation of the piston head 102 during its upstroke.

A check valve is supplied in the said conduit 120 and may be of the ball type including an enlargement 132 of the said bore of the conduit 120 with a conventional ball valve member 134 freely floating therein. A suitable spider 136 is also supplied in the enlargement of the bore, permitting only a selected length of travel of the ball 134.

An elbow 138 may be threadedly received in the cylinder block 108, communicating with the said bore 114. This elbow has a transverse pipe 140 connected thereto with a conduit 142 operatively connected therewith and with a block 144.

The said block 144 has a passage 146 therein, which is in direct communication with the bore of the said pipe or conduit 142. This passage terminates in an enlargement thereof 148 which has a port 150 directly communicating therewith.

It may now be seen that on the downstroke of the piston head 102 the plastic material (preferably metallic and in the molten or semi-molten stage) is urged upwardly through the passage 146, thence through the port 150 into a mold 152.

A plug 154 is threadedly received in one end of the enlargement 148 for access to this enlargement. A second port 156 communicates with the said enlargement 148 and is on the opposite side thereof from the said port 150. This last-mentioned port 156 communicates with a valve chamber 158 formed in the said block 144 wherein a ball valve member 160 resides. This ball is freely floatable between the said port 156 and a valve seat 162, which valve seat has a passage 164 directly communicating therewith.

The said passage 164 has a chamber 166 communicated therewith and a conduit 168, threadedly received in the said block 144, is in communication with the said chamber 166. This conduit 168 terminates adjacent the bottom portion of the crucible or melting pot 36 for receiving molten material therefrom. It will be noted that upon reciprocation of the piston head 102, a charge of material is received from the crucible through the various passages, conduits and valves described above. In operation, a certain amount of leakage will occur between the piston head 102 and the cylinder walls. To regulate the inflow of plastic material from the crucible in order to separate the desired amount of material, which separation should be substantially similar at all times (in quantity), the conduit 120 with its valve mechanism is supplied. Regulation of the valve stem 124 serves this purpose.

In fabrication of this described portion of the invention, various expedients might be resorted to for feasibility of manufacture, such as the utility of a plug 170 closing the upper portion of the valve chamber 158 after positioning the valve ball member 160 therein.

Lubricating system

In operation of the invention, it is necessary to lubricate certain elements of the invention. This end is accomplished by means of applying lubricant to the molten material before it is separated in charges. The preferred form of lubricating system forms an important part of the present invention and will be described in detail at this time.

A lubricant container 172 having a spout 174 is supplied. This container also has a spider element 176 therein with an internally threaded boss 178 substantially centrally thereof. A valve stem 180 having a threaded portion 182 is threadedly received in the said internally threaded boss 178. The said valve stem 180 may be supplied 65 with a bent portion 184 at one end thereof and a reduced valve head portion 186 at the opposite end. The said valve head portion is cooperative with one end of the bore in the spout 174 in order to effect the proper and desired valving.

As is seen in Figure 9, the lubricant extends 70 through the said spout 174 and progresses to the chamber 166. By proper manipulation of the valve stem 180, the rate of flow of lubricant is selectively regulated.

Upon actuation of the piston head 102, the molten material is urged through the said conduit 142 and finally through the mold 152 as described above. At the same time, the lubricant from the chamber 166 is intermingled or admixed 75 with the molten material going through the vari-

ous passages of the block 144 with the molten material. It is noted at this point that a certain amount of lubricant will seep through the conduit 142 for lubrication of the piston and cylinder walls.

Cooling system

Viewing Figures 3, 6 and 9 primarily, it will be seen that a water conducting pipe or tube 188 extends from a suitable source of water or other cooling fluid. A valve generally indicated at 190 (see Fig. 1) is supplied in this water pipe 188 for the control of the flow of fluid therethrough as well as the rate of flow. This pipe extends around one end portion of a mold cell 192 which accommodates the said mold 152. The said tube 188 extending around the mold cell 192 forms a coil 194 which may be welded thereto or otherwise secured, such as by means of a suitable small welded bracket or plate 196. Obviously, the terminal of the said mold cell 192, and therefore the mold 152, is maintained in a cool condition at this point in order to solidify the issuing molten material. The previously described burners and burner pipes 66 and 68, respectively, terminate adjacent the said block 144 and the mold cell 192 in order to maintain the molten material in the fluid stage. However, the opposite end of the said mold and mold cell are intentionally cooled for solidifying the material. Thus, in accordance with the particular shape of the mold aperture 198, various shapes and sizes of strips may be formed.

In order to ascertain when the molten material is transferred to this stage, which is appropriate for efficient operation of the machine, a well 200 may be rigidly attached to or formed integral with the mold cell 192 and a small quantity of the molten material placed therein as a sample. When this sample attains the proper fluidity, it may be viewed directly in this well or recess.

The terminal of the said water tube 188 may be adjacent a funnel-shaped element 202 which is attached to a drain pipe 204. The said drain pipe 204 may again be fixedly secured to the frame or support by means of a conventional bracket 206 which is attached to the cross support 42. The drainage is, of course, received in a suitable trap, which may be supplied in the floor, through a wall, or any other suitable place. Since the water circulating through the cooling system is relatively clean, no special provision may be necessary for filtering or otherwise purifying this water.

Mold cell and adjustable mounting therefor

The said mold cell 192 is juxtaposed relative to the said crucible 36 and has a slot 208 therein for accommodation of a conventional mold 152. In order to form various sized strips of material, the mold cell 192 may be removed in favor of other size molds. Of course, the size is determined by the length and width of the aperture 198 therein. The mold 152 is frozen in the mold cell 192 by means of placing a bit of the molten material in the aperture 208 and permitting it to freeze by the action of the cooling jacket 194. This of course maintains the mold firmly in position in the cell. However, it is seldom that the mold 152 is perfectly placed in the mold cell 192 whereby alignment with the necessary cooperating elements of the apparatus is perfect.

Therefore, a means for aligning the entire cell 192 with the necessary other elements of the de-

vice is supplied. Accordingly, the present invention has incorporated therewith means for adjusting the entire cell 192 after the mold 152 or a mold of a different description is placed therein. This means may be seen best in Figures 6 and 15, wherein an arm 210 extends from the block 144 to one side of the frame or support. The block 144, and consequently the attached or integral mold cell 192, may either be shimmed at the connection of the arm 210 and the side of the support or, if it is found desirable, the bolt 212 may simply threadingly adjust the cell 192. The mold cell 192 may be additionally supported by means of a rod or bracket 214 which attaches to the mold cell and to one of the supporting elements forming a portion of the support.

This feature of the invention is of material importance, since the strip which is formed and cut should align substantially perfectly with a puller and holder mechanism to be described subsequently.

Motor and drive mechanism

Referring primarily to Figures 1 and 3, a simplified means for actuating various and sundry mechanisms pertinent to the present invention is illustrated. The motor 20 is attached to the platform 18 as described above and the V-groove belt 30 is actuated thereby. This belt is also entrained about a relatively large pulley 220 which is journaled on a suitable shaft 222, journaled in turn in the said support. The said shaft 222 has a worm 224 secured thereto which is in engagement with a gear 226. The said gear 226 is in turn journaled on a shaft 228. This last-mentioned shaft has its axis extending transversely of the longitudinal axis of the said shaft 222 for transmission of torque. A cam 230 is fixedly secured to the said shaft 228, engaging a cam follower 234. This last-mentioned element 234 is journaled on one end of the said rocker arm 82, the opposite end thereof being fitted in the said notch 80 as described elsewhere in the specification. At a point substantially medially of the length of the rocker arm 82, there is a pivot pin supplied which is journaled in a conventional bracket 238. This bracket may be attached to any suitable portion of the said support, preferably the cross element 42. It is now seen that upon rotation of the shaft 228, the rocker arm 82 will be actuated for supplying reciprocatory movement to the piston rod 88.

Also secured to the said shaft 228 is an eccentric 238 having a pitman 240 secured thereto. This pitman has a cam lobe 242 formed thereon which is adapted to engage the cam follower 244 for the purpose of actuating a cutter mechanism to be described subsequently.

The opposite end of the said pitman 240 is connected with a linkage which in turn actuates a puller mechanism.

Puller mechanism

Attention is now directed primarily to Figures 7 and 8 wherein a puller mechanism is illustrated for use in forming a portion of the present invention. A strip 246 which is formed by receiving the hardened metal or other plastic material from the mold 152 is shown in use in these views of the invention. The puller mechanism consists of a base plate 250 having a relatively stationary block 252 integral therewith. A sliding or locking block 254 is positioned adjacent the said relatively stationary block 252 for cooperation therewith.

The entire mechanism including the base plate

250 is periodically slideable by means of a portion of the structure described previously and by other structure to be described subsequently. As the plate 250 and its pertinent mechanism is slid forward, the sliding block 254 is clamped toward the relatively stationary block 252 with the strip of material 246 therebetween. This pulls the strip 246 from the mold 152 intermittently. When the plate 250 is returned, the said sliding block and stationary block are so arranged as to permit the strip 246 to move therebetween freely. The specific structure for carrying out this function may be seen best in Figure 8 wherein a stub shaft 256 is journaled in the base plate 250 and the cover 258. This stub shaft 256 may have reduced terminals with an enlarged portion therebetween. The enlarged portion has an internally threaded bore for reception of a threaded element or screw 260. An enlargement or ball 262 is formed at one end of the said screw 260 and cooperates with a socket or recess 266 formed in the said sliding block 254. The said screw 260 is thereby adjustable in the stub shaft 256 for compensating for various widths of strips 246 which are cast.

Of course, one end of the said threaded element 260 may be slotted for reception of a screwdriver or the like in adjustment. Other expedients such as forming a knurled knob on the end of this element may be resorted to if it is found desirable.

The longitudinal axis of the said threaded element 260 is maintained off center relative to the longitudinal axis of the said plate 250 in order that upon forward movement of the entire plate 260 the sliding block 254 will tend to frictionally engage the strip 246, locking it in place, in carrying the said strip with the entire pulling mechanism.

In order to further insure a firm frictional tendency for engagement with the strip 246, a resilient element 268 is secured to the said plate 250 for resiliently biasing the sliding plate 254 in a selected direction. This resilient element 268 may be in the form of a strip having a loop 270 at one end thereof which encircles a stationary pin 272 either formed integral with or secured to the said plate 250. A guide post 274 is secured to the upper surface of the said plate 250 for guiding the said resilient element 268. The opposite end of the said resilient strip 268 may be received in a suitable recess in one edge of the said sliding block 254, being normally maintained therein due to the inherent resiliency of the metallic strip 268.

It will be seen that the stripped down plate 38 is formed with a recess 276 for accommodation of a portion of the pulling mechanism. A tie bar 278 extends from the plate 250 and is received within the said recess 276. Guide plate 282 and the end surface 284 of the plate 250 together with the raised extension 286 are positioned on opposite sides of this tie plate 278 flanking the said plate 38 to form a guide for the pulling mechanism.

A mandrel-shaped pin including an enlarged section 284 and a relatively reduced section 286 is secured to the said plate 282 for accommodation of the actuating means for the entire pulling assemblage. Since it is essential that all of the elements of the present invention are synchronized in movement, the means for actuating the pulling assembly is adjustable in nature in order to compensate for speed differentiations and also to compensate for stroke adjustment of this mechanism.

The said pitman 240 has a stroke adjuster piv-

oted thereto. This stroke adjustor may be seen best in Figures 4 and 5, as well as in Figure 2. It consists of a housing generally indicated at 290 with diametric pins 292 and 294, respectively, extending therefrom. These pins are journaled in a suitable bracket 296 which is attached to the plate 38 through the medium of suitable bolts terminating in the threaded apertures 298 and 300 respectively. The said housing includes a cover plate 302 which has an aperture adjacent its terminal portion and it is this aperture wherein a suitable pin pivotally connects the pitman 240 and the housing 290. Since the pitman 240 is mounted on the eccentric 238, a definite orbit of travel is provided for this pitman. The end of the pitman being attached to the plate 302 actuates the plate in a rocking movement.

A tie rod 304 is pivotally secured to the enlarged portion 284 of the said pin of the puller mechanism and may be maintained in place through the medium of a conventional cotter pin or the like. The opposite end of the actuation rod 304 is pivotally secured in a shoe 306 which slides in the housing 290.

Means for adjusting the shoe 306 in this housing 290 is supplied. The preferable means consists of a screw 308 which is adjustably received in the housing 290 and more specifically through one wall thereof, one end of which may have a knurled knob 310 or the like thereon. The opposite end of the screw 308 has a reduced portion 312 therein for accommodation of a pin 314. This pin of course is freely slideable in the reduction 312, while the pin is also rigidly associated with the said shoe 306. Upon manipulation of the knurled knob 310, the entire shoe 306 may be raised and lowered within the housing 290, thereby adjusting the longitudinal axis of the actuation rod 304 toward and away from the pivotal axis of the housing 290 which is obviously the axis of the diametric pins 292 and 294. By this expedient, the stroke of the puller mechanism is regulated both as to speed and length.

In order to maintain the puller mechanism in its desired travel, a small rail 316 is secured to the base bar or plate 38 spanning the said recess 276. Of course, the rail 316 is received between the said plates 280 and 282 in reciprocation of the pulling mechanism.

The holding mechanism (see Fig. 14) is identical to the pulling mechanism including the exact structure thereof. Of course, the holding mechanism does not reciprocate, and therefore no means is provided for this purpose. It is, however, adjustable by manipulation of its screw or threaded element equivalent to that element 260. This compensates for various widths of strip which is molded in the apparatus.

As the pulling mechanism is actuated, the strip 246 is pulled through the holding mechanism, which permits it to move freely (the strip) therethrough. However, when the pulling mechanism returns in a single cycle of operation, the said holder firmly (frictionally) grips the strip 246, allowing the said pulling mechanism to return without applying a force on the strip 246 in the undesired direction.

Cutting mechanism

A cantilever 318 is secured to the table top or support top 332 by any suitable means such as screws 320 in order to accommodate a sliding bar 324. This sliding bar or rod has a stop 326 secured thereto and is adjustable relative to the longitudinal axis of the said sliding rod or bar

324. The said stop may be in the form of a small bracket or the like having a set screw 328 therein. Of course, the set screw frictionally engages the bar 324, thereby permitting the stop to be placed substantially in any position on the bar. This stop is adapted to be engaged by the issuing strip 246 after it has been pulled and held as described above. When the strip issues to a position whereby contact with the stop takes place, the entire bar 324 is urged forward, carrying with it an adjustable cutter mechanism. A screw 330 or other suitable pivotal connection is effected between the sliding bar 324 and a framing element 332 of the cutter mechanism.

The specific structure of the cutter mechanism may be seen best in Figures 10-13 wherein the framing element 332 is integrally associated with a body portion 336. This body portion has a notch 338 therein which is slidably received in a recess 340 formed in the said plate 38. The entire body portion 336 is slidable with the actuation bar 324, limited by the confines of the said recess 340.

A cutter 342 is supplied with slots 344 and 346 respectively. These slots accommodate bolts 348 and 350 respectively which are anchored to the body portion 336. Interposed between the cutter or knife 342 and the body portion 336 is a guide plate 352. This guide plate is formed with slots 354 similar to the said slots 344 and 346 and which also have the said bolts 348 and 350 extending therethrough.

The said guide plate 352 is formed with a slot 358 therein for receiving the strip 246 therethrough, for subsequent cutting operations. Of course, the edge of the cutting blade 342 may be beveled for more effective shearing of the strip.

As is seen in Figure 6, the cutting mechanism is then responsive to a predetermined length of strip 246 which is extruded from the mold. As the strip 246 engages the stop 326, the bar 324 is urged in the cantilever support 318, thereby carrying with it the cutting mechanism. Viewing Figure 1, it is readily appreciated that the cutter 342 is so positioned as to be contactable with an actuating hammer 360. This hammer is constantly moved back and forth until the cutter mechanism is pulled to a position whereby contact of the hammer 360 and the cutter 342 is effected. At that time, the shearing of the strip 246 takes place.

In order to compensate for various widths of strip to be cut, the guide plate 352 may be adjusted and maintained in the adjusted position by means of the shim 362 seen in Figure 13. This shim has a centering plate 364 secured thereto by means of a suitable screw or the like 366 and also has a hole 368 formed therein. This hole is adapted to encircle the pin 370, which pin is in turn secured rigidly to the main body 336 of the cutter mechanism.

The said slot 358 receives the strip 246 preparatory for shearing. When a very wide strip is used, the adjustment of the guide plate 352 is as seen in Figure 12. However, when it is desired to cut relatively narrow strips, the shim 362 is removed from the notch 374 and placed on the opposite side of the element 332. Of course, prior to the placement of the shim 332 on the opposite side of this element, the entire plate 352 is slid on the bolts 348 and 350 to form a notch on the opposite side of this element. Then, the width of the slot 358 is reduced effectively due to a portion of the main body portion 336 which overlies a portion of the said slot 358. Then,

it is obvious that a more narrow strip may be cut without the bending which would result in a loose fit.

The cutter 342 has a post 376 extending therefrom and a spring 378 or other equivalent resilient biasing means attached thereto. A second post 380 is rigidly attached to the main body 336 of the cutter mechanism and also forms an anchorage for the spring 378. Upon movement in a single direction of the cutter 342 against the normal biasing force of the spring 378, the strip will be sheared and upon release of this force which urges the cutter 342, the said cutter will be returned to the inoperative position.

Means for maintaining the travel of the strip in a predetermined path is supplied. Often strips, when cut, will fall in such a manner as to prevent the free issuing of the continuous strip from the mold adjacent this cutter mechanism. Therefore, a specially devised baffle has been supplied in association with the cutter mechanism for preventing this inadvertent falling. The baffle 382 has a flared shoulder 384 associated therewith which engages the side of the issuing strip. As the continuous strip moves through the cutting mechanism, it is guided by means of the baffle 382 which is pivoted to the main body portion of the cutter mechanism 336 by a suitable bolt, pin or the like. It is not essential to move the baffle with the adjustment of the plate 352, since the curved or flared portion covers sufficient area to compensate for various plate 352 adjustments. This baffle simply prevents cut strips from falling backward to prevent the unobstructed travel of the continuous strip in its issuing movement.

In order to guide the cutting mechanism in its travel, a small bracket 386 is secured to the said plate 38 and is adapted to encircle the extension 388 of the said main body portion 336. In reciprocation of the cutting means, this guide or bracket 386 maintains the cutting mechanism in the desired travel or orbit.

Means for resiliently returning the cutter mechanism to the inoperative position after it has sheared the strip 246 is supplied. This means may be seen best in Figure 6 wherein a relatively long spring 390 is illustrated as being secured to the said bracket 386 and also secured to an adjustable stop 392. This last-mentioned stop 392 is secured to the sliding rod 324 by any suitable means. As the rod 324 is progressed forward through the medium of the issuing strip 246, the spring 390 is stretched or deformed, constantly applying a returning force to the said rod 324. After the strip is sheared, there is no force urging the rod 324 against the normal or inherent resiliency of the spring 390 and therefore, this spring returns the rod and cutting mechanism to the inoperative position.

Referring now to the hammer 360 mentioned hereinabove, attention is directed primarily to Figures 1 and 3. Here the hammer 360 is shown as simply a bar connected to a rocker shaft 396. This rocker shaft is mounted on suitable perches 398 and 400, respectively, which are, in turn, attached to the said support. If it is found desirable, the said rocker shaft 398 may be L-shaped with the above mentioned cam follower (in the form of a roller) 244 attached thereto. This cam follower engages the said cam lobe 242 intermittently during the movement of the pitman 240 in its cycle of operation.

It has been found expedient to utilize a straight hammer 360 in lieu of the L-shaped rocker shaft 396, with the roller 244 attached directly thereto.

Of course, this would require a slight alteration as to the shape, position, and size of the cam lobe 242. With the described mechanism, however, it is readily understood that it is within the purview of the invention to adjustably mount the hammer 360 on the shaft 396 to regulate the stroke of the hammer. This is but an expedient which may be resorted to if it is found desirable.

It is readily appreciated, upon inspection of Figure 3, that the cutter 342 may be moved as described above until the hammer (which is intermittently actuated as described) comes into such a position as to be contacted by this hammer.

Manual priming device

A latch keeper 402 is secured to the said support by any suitable means, such as welding, bolting or the like. This latch keeper has a notch 404 formed therein for accommodation of a lever 406. The said lever 406 is pivoted to a suitable perch 408 which is, in turn, secured to the said support member 42. When it is desired to prime the device, the said lever 406 is actuated about its pivot pin 410 as an axis for raising and lowering the rocker arm 82. A reduced terminal portion 412 engages the under surface of the said rocker arm 82, lifting the piston rod 88 therewith through the intermediate structure. The device should be manually primed before set into operation in order to test whether the material in the crucible or melting pot 36 is in the proper stage of fluidity. Further, the invention may be manually primed by actuation of the lever 406 for setting the mold 152 in the mold cell 192.

It will be noted that the arrangement of elements in the present invention is so supplied that the entire device may be set into operation by one individual. The switch may be actuated for the motor 20 from one side of the invention, the heating means rendered operative from the same side and the invention may be primed from that particular side. The mold may be set in place and the various other adjustments such as the regulation of lubricant flow may be easily effected.

Operation

A supply of material is placed in the crucible 36 and heated to the desired state of fluidity. Of course, the heating occurs by means of the furnace and burner construction as described previously. Manual priming is then the next stage of operation and the mold of the desired size and characteristics is seated in the mold cell. The water supply is permitted to flow through the coil 194 in order to cool a portion of the mold and mold cell to form the strip 246.

The piston rod 88 is actuated by the mechanism described and the power stroke of the piston is effected by means of the potential energy stored in the spring 160. On the downstroke of the piston, the molten or semi-molten material is forced through the pipe 142 and into the elbow 118, whence the check valve ball 134 impedes further flow through this elbow 118. The material flowing through the pipe 142 urges the ball check valve element 160 into its associated seat 162, thereby forcing the charge of material to be projected through the mold 152.

On the upstroke of the piston 102, material is received through the pipe or conduit 160 as well as through the channels 128 and 130. The lubricant is, of course, permitted to drip and/or be sucked into the system through the spout 174.

It is noted that the port 156 is so arranged in the block 144 that the ball 160 will not normally close the said port 156 on the upstroke of the piston 102. In order to compensate for the leakage as described above the regulation of the valve stem 124 may be effected at this time.

As the resultant strip is formed, it is intermittently pulled by the puller mechanism and held by the holding mechanism. The said strip then proceeds to the cantilever support, whereupon the cutter mechanism, responsive to the length of travel of the issuing strip, is rendered operative. When it is desired to cut a predetermined length strip, the stop 326 is slidably adjusted on the actuating rod 324, thereby rendering the response of the cutting means earlier than when a relatively longer strip is desired.

The length of strip which is desired is sheared at this time and prevented from falling backward to obstruct the free travel of the continuous strip. Of course, as described above, the cutting mechanism is resiliently returned when the pre-selected length of strip is cut.

In pulling the strip 246 from the mold, it is sometimes desirable to stop this operation for a duration. Under such circumstances, the bracket 416 forming a latch which is pivoted to the base plate 250 of the puller mechanism is pivotally actuated for engagement with the threaded element 260, thereby maintaining it in the inoperative position relative to the sliding block 254.

While there has been described and illustrated but a preferred form of the invention, it is apparent that certain variations may be made without departing from the spirit thereof. Accordingly, limitation is sought only in accordance with the scope of the following claims.

Having described the invention, what is claimed as new is:

1. In an apparatus for forming strips of material which includes a support, means carried by said support for intermittently pulling one of the strips including a base plate with means for reciprocating said base plate, a bearing block for the strip secured to said plate, a strip locking block, a pivot carried by said base plate with a member adjustably carried thereby and operatively connected with said locking block and mounting said strip locking block on said plate such a distance from said bearing block as to cause binding of the two blocks with the strip therebetween when moving the locking block with respect to and toward the bearing block by moving said plate forward in a part of a single reciprocatory cycle of operation, and a spring reacting on said base plate and said locking block constantly urging said locking block toward said bearing block.

2. In an apparatus for forming strips of material which includes a support, means carried by said support for intermittently pulling one of the strips including a base plate with means for reciprocating said base plate, a bearing block for the strip secured to said plate, a strip locking block, means adjustable toward said bearing block for slidably mounting said strip locking block on said plate such a distance from said bearing block as to cause binding of the two blocks with the strip therebetween when moving the locking block with respect to and toward the bearing block by moving said plate forward in a part of a single reciprocatory cycle of operating, a spring reacting on said base plate and said locking block constantly urging said locking

block toward said bearing block, and means carried by said support for holding the pulled strip comprising a plate secured to said support with a fixed block secured thereto, a sliding block secured to said last-mentioned plate and cooperating with said fixed block, and said fixed block and said sliding block forming jaws for holding the pulled strip while the pulling means is operating in the return movement in the single cycle of operation.

ANTON H. NARROW.
